UNITED STATES PATENT OFFICE

EDGAR V. McCARTY, OF LOS ANGELES, CALIFORNIA

ATTACHMENT FOR AUTOMATIC PISTOL HANDLES

Application filed June 20, 1931. Serial No. 545,743.

This invention relates to automatic pistols and has for its object the production of a simple and efficient attachment which is adapted to be secured to the rear portion or 5 rear face of an automatic pistol handle, so as to slightly elevate the gun barrel while handling the pistol or gripping the same by the hand.

Another object of this invention is the 10 production of a simple and efficient attachment which will conveniently fit upon the rear face near the lower end of the handle of an automatic pistol, so as to cause the barrel to be slightly elevated when gripped 15 by the hand of an operator, thereby greatly facilitating the accurate firing of the gun.

It has been found by actual experience in 20 handling automatic pistols and the like that when firing the pistol at random or taking aim quickly, the shot fires low due to the fact that in suddenly gripping the pistol for the 25 purpose of taking quick aim, the barrel invariably is lowered. By attaching the wedge shaped attachment to the rear of the handle, the operator will tend to raise the point of 30 the barrel due to this enlargement which may be attached to the rear portion of the handle of the barrel, such as an automatic pistol and the like, of the standard type now placed upon the market.

With these and other objects in view, the invention consists in certain novel constructions, arrangement, and combination of parts, which will be fully described.

35 In the drawing:—

Figure 1 is a side elevation of the revolver of the automatic type.

Figure 2 is a rear elevation thereof.

40 Figure 3 is a bottom plan view of the handle portion.

Figure 4 is a perspective view of the enlarged wedge adapted to be secured to the lower rear end of the handle of the automatic revolver.

45 By referring to the drawing it will be seen that 1 designates the usual automatic revolver of the standard type to which is secured the enlarged wedge 2, this wedge being shaped upon its inner face 3 to conform to 50 the contour of the rear face of the handle

of the pistol 1. The enlarged wedge 2 preferably tapers toward its upper end 4 and is provided with a curved lower end 5 to fit snugly around the under portion of the handle of the pistol 1 and tends to resist an upward movement of the wedge 2 relative to the handle of the gun. Tap screws 6 are countersunk within the enlarged wedge 2 and pass therethrough and fit in the threaded socket 7 formed in the handle of the gun for efficiently attaching the wedge to the handle of the gun. 55

It should be understood that certain detail changes in mechanical construction may be employed without departing from the spirit 60 of the invention, so long as these changes fall 65 within the scope of the appended claim.

By means of the present device it has been found by actual experience that the accuracy of firing a gun, particularly of the pistol type 70 will be greatly increased, particularly when the gun is fired at random or aim is taken quickly. Through the medium of this wedge shaped structure which may be attached to a gun of the standard type, the common fault 75 of dropping the muzzle of the gun too low to obtain an accurate shot may be readily remedied simply by the addition of the wedge shaped enlargement indicated by the numeral 2 and above described.

Having described the invention, what I 80 claim as new is:

As a new article of manufacture, an elongated tapering wedge adapted to be secured to the rear face of the handle of an automatic 85 pistol, said elongated tapering wedge provided with a curved inwardly dished lower end adapted to fit around and snugly engage the lower rear corner of a piston handle facilitating the holding of the wedge in position 90 upon the handle of a pistol and leaving the lower end of the handle free for the insertion of cartridges.

In testimony whereof I affix my signature.

EDGAR V. McCARTY.
